UNITED STATES PATENT OFFICE.

KENNETH H. LOVELL, OF LIBERTYVILLE, ILLINOIS.

COLLAPSIBLE REINFORCEMENT FOR CONCRETE.

Application filed July 24, 1926. Serial No. 124,597.

My invention relates to improvements in reinforcements for concrete constructions, the same being particularly adapted for use in reenforcing floor beams and other spans, but being capable of use in various other constructions, such, for example, as walls, slabs, arches, etc., my purpose, generally speaking, being to provide a reenforcement which is inclusive of shear and tension members so foldably or collapsibly connected together that when the reenforcement is set up for use it forms a cage-like structure of generally U-shaped cross section, and when folded or collapsed the tension and shear members serve to protect one another against injury and the entire structure occupies a minimum amount of space, so that its storage, transportation and handling is greatly facilitated.

Moreover it is my purpose to provide a reenforcement which is simple in construction, relatively cheap and easy to produce, strong, thoroughly reliable and efficient in use, and in which the tension members may be adjusted readily to different positions with respect to the shear members either to lock the reenforcement against collapse from a set up position or to permit it to be collapsed.

With the foregoing and other purposes in view, my invention consists in the novel features of construction, combination and arrangement of parts as will be hereinafter more fully described, illustrated in the accompanying drawings and defined in the appended claims.

In the drawings, wherein like characters of reference denote corresponding parts in the different views:—

Figure 1 is a perspective showing my invention used as a floor beam reenforcement; Fig. 2, a side elevation of my reenforcement in a folded or collapsed condition; and Figure 3, a top plan of my reenforcement as shown in Figure 2.

By reference to the drawings, it will be observed that my improved reenforcement consists essentially of a plurality of shear members 10 and a plurality of tension members 12. Each shear member is formed from a single length of material bent substantially into U-shape and comprising a pair of spaced vertical bars 14, 14 and a horizontal bar 16 connecting them at their lower ends, the upper ends of said vertical bars terminating in outwardly and downwardly

directed portions 18, 18 of limited length, as shown.

The horizontal connecting bar 16 is of less length than the distance between the vertical bars, 14, 14, and terminates at its ends in short downwardly directed portions 20, 20, which in turn are extended outwardly and thence upwardly into the vertical bars 14, 14, the result being that, as aforesaid, each shear member is of substantially U-shape with the legs or vertical bars 14, 14 thereof connected with the straight portion or horizontal bar 16 thereof through small U-shaped bends. Bar 16 acts as support for longitudinal reenforcing, doing away with individual supports commonly used to hold the device off from the wood form so as to allow flow of concrete as required by city ordinance in connection with fire-proofing.

The tension members 12 are four in number in this instance, although this number may be increased or decreased as desired, and they preferably but not necessarily are in the form of straight, flat bars of any desired length punched at evenly spaced intervals to provide tongues 22 which are bent around the vertical rods 14, 14 of the shear members 10 whereby the latter are connected together and held in spaced relation to one another, and whereby the reenforcement may be manipulated between the set up and collapsed positions shown, respectively, in Figures 1 and 2 of the drawings.

The tension bars 10 are placed against the inner faces of the vertical bars 14, 14 of the shear members and the tongues 22 extend around the outer faces of said vertical bars, so that when the reenforcement is collapsed the tension bars lie flat against one another and the shear members extend diagonally, the result being that the shear members serve as protecting reenforcement for the tension members and the latter serve in the same capacity for the shear members.

Two tension bars preferably are connected with each vertical bar 14 of the shear members, one near the top and one near the bottom of each vertical shear bar, and due to the friction produced by bending the tongues 22 around the shear bars the tension bars will remain in any position they may be placed along the shear bars. It is to be noted, however, that the hinge connections provided by the tongues 22 permit the tension bars to be shifted to any de-

sired position along the vertical shear bars, and thus it is apparent that after the re-enforcement has been set up the lower tension bars may be forced downwardly so as 5 to lie within the small U-shaped bends between the vertical bars 14, 14 and the horizontal bars 16 of the shear members as shown in Fig. 1 to lock the reenforcement against collapse from its set up position. 10 Of course, the reenforcement may be used with the tension bars positioned anywhere along the bars 14, 14, and since it will rarely be required to collapse the reenforcement once it has been set up for use, the tension 15 bars normally will be positioned above the U-formations between the ends of the bars 14, 14, 16, so that all that is necessary to lock the reenforcement against collapse is to force the lower tension bars downwardly 20 following setting up of the reenforcement from the position of Figures 2 and 3 to the position of Fig. 1.

The manner of using a reenforcement of the type I have disclosed is well known to 25 those skilled in the concrete construction art and further description is therefore deemed to be unnecessary.

I claim:

1. A reenforcement for concrete constructions including a plurality of generally U-shaped shear members, a plurality of tension members connecting said shear members together, hinge joints between said tension and shear members permitting the re-

enforcement to be collapsed, and means 35 whereby the tension members may be interlocked with said shear members to prevent collapse of the reenforcement.

2. A reenforcement for concrete constructions including a plurality of generally U- 40 shaped shear members each including a pair of spaced vertical shear bars and a horizontal bar connecting them, tension members connecting said shear members, said tension members having hinge connections 45 with the vertical bars of said shear members and being movable to different positions along said vertical bars, and means effective in a given adjusted position of said tension members along said vertical shear bars to prevent relative rotation between said shear and tension bars, thereby to prevent collapse of the reenforcement from a set up position. 50

3. A reenforcement for concrete constructions including a plurality of generally U-shaped shear members each including a pair of spaced vertical shear bars and a horizontal bar connecting them, U-shaped formations between the ends of said horizontal bar and said vertical bars, and tension members hinged to said vertical bars and movable along the latter into and out of engagement with said U-shaped formations. 55

In witness whereof, I have hereunto subscribed my name.

KENNETH H. LOVELL.
